UNITED STATES PATENT OFFICE.

EDWARD I. BRADDOCK, OF WINCHESTER, MASSACHUSETTS, ASSIGNOR, BY DIRECT AND MESNE ASSIGNMENTS, TO LAMB & NASH COMPANY, OF KITTERY, MAINE, A CORPORATION OF MAINE.

SHEET-METAL HOOP.

1,173,705.

Specification of Letters Patent.

Patented Feb. 29, 1916.

Application filed April 26, 1912. Serial No. 693,323.

To all whom it may concern:

Be it known that I, EDWARD I. BRADDOCK, a citizen of the United States, residing in Winchester, county of Middlesex, and State 5 of Massachusetts, have invented an Improvement in Sheet-Metal Hoops, of which the following description, in connection with the accompanying drawings, is a specification, like letters on the drawings representing like parts.

This invention relates to a sheet metal hoop for barrels, tubs, pails and the like, and has for its object to provide a sheet metal hoop, which is light, inexpensive, 15 strong and especially applicable for use as the chime hoop. To this end the hoop is made from a sheet metal blank or strip, and is provided at one side or edge with a fold, which is corrugated or bent transversely to 20 form outwardly extended striking projections, for the reception of blows of a hammer or other tool, by which the hoop may be driven onto the barrel or other receptacle. The ends of the band or strip may be secured together in any suitable manner, but 25 it is preferred to fasten them together by means of a key, which is crimped to lock it against accidental displacement, as will be described. The sheet metal hoop may be 30 reinforced at its folded edge by a wire, which is located in the fold as will be described. These and other features of this invention will be pointed out in the claims at the end of this specification.

Figure 1 is an elevation of a portion of a barrel provided with a hoop embodying this invention. Fig. 2, an enlarged plan of a portion of the hoop shown in Fig. 1. Fig. 3, an enlarged elevation of the portion of 40 the hoop shown in Fig. 2. Fig. 4, a longitudinal section on the line 4—4, Fig. 3. Fig. 5, an enlarged cross section on the line 5—5, Fig. 3. Fig. 6, a plan of the hoop shown in Fig. 1. Fig. 7, an enlarged detail in section 45 to be referred to, and Fig. 8, a detail of the blank from which the hoop is formed.

Referring to the drawings, *a* represents a sheet metal hoop embodying this invention. The hoop *a* is provided at one edge with 50 a folded portion, preferably shaped to form a hollow bead *b* substantially circular in cross section and in which is located a wire *c*, and the folded portion is made of sufficient width to form a flange or lip *d*, which ex-

tends from the bottom of the bead *b* and 55 is pressed against the body portion 10 of the hoop to obtain a hoop having a body portion provided with a double thickness of metal below and in the immediate vicinity of the bead in the hoop so as to materially strengthen the body portion of the 60 hoop at its upper end. The bead *b* and the wire *c* contained therein are corrugated or bent to form outwardly extended projections 12, which form striking projections 65 for the reception of the blows of a hammer or other tool, by which the hoop may be driven onto the barrel 13 or other receptacle.

Provision is made for the ends of the bead *b* to be brought close together while allowing for the overlapping of the ends of the 70 hoop. For this purpose, the sheet metal portion of the hoop is made from a sheet metal blank or strip 14, see Fig. 8, which has portions removed from one side at its 75 opposite ends, to form end portions 15, 16 which are narrower than the intermediate body portion of the strip or blank, so as to form a projecting portion 17 at one side of the strip or blank, which is employed to 80 form the hollow bead *b* and the lip *d*. The ends 15, 16 of the metal strip or blank are designed to overlap and may be fastened together in any suitable manner, but it is 85 preferred to secure them together by a metal key 18, which is passed between retaining webs 19, formed by making a plurality of parallel slits 20 in the end portions 15, 16, as shown in Figs. 3, 4 and 5. To prevent the key 18 from being accidentally 90 displaced, it is bent or crimped between its ends, after the manner represented in Fig. 5, to form a plurality of locking shoulders 21 which engage the walls of the slits 20 in the end portions 15, 16. The key may 95 be bent or crimped by subjecting the overlapping ends 15, 16 to one or more blows on the inner side of the hoop, and these blows may and preferably will be sufficiently heavy to bring the webs 19 on the 100 inner side of the key substantially flush with the inner side of the hoop, so as to leave the hoop smooth on the inner surface and enable it to lie close to the barrel at the overlapping end portions.

In the manufacture of the hoop shown in Fig. 1, the projecting edge portion 17 of the blank or strip 14 is folded about 105

the wire *c*, which is arranged with relation to the blank 14, so that the ends of the folded bead *b* are bridged by the wire, whose ends meet at a point in the bead 5 where the latter is not broken as represented in Fig. 7.

From the above description, it will be observed that the body portion of the sheet metal hoop may be made thin and light, 10 while its folded edge portion is materially strengthened and capable of withstanding a severe blow, which especially fits the hoop for use as a chime hoop, while the outwardly extended projections 12 afford substantial 15 surfaces for receiving the blows of the hammer or other tool with which the hoop is driven onto the barrel. While it is preferred to use the reinforcing wire *c*, it is not desired to limit the invention in this respect, as a very serviceable hoop may be produced from the sheet metal blank alone, 20 by providing the corrugated bead at one edge.

By reference to Figs. 1 and 3, it will be observed that the flange or lip *d* practically forms at the upper part of the body portion of the hoop a supplemental hoop, which is in contact with the body portion of the main hoop in the immediate vicinity of the fold 30 or bead, and, as a result, this lip or flange materially strengthens the body portion of the hoop just below and in the immediate vicinity of the fold or bead and reinforces the body portion of the hoop so as to prevent 35 the upper portion of the body portion of the hoop being bent outwardly away from the barrel when the chime hoop is driven onto the same and the upper portion of the chime hoop is not supported by the barrel.

40 Claims:

1. A metal hoop comprising a sheet metal band or strip having at its opposite ends, portions which are narrower than the intermediate portion of said strip to form on 45 one side of the strip a projecting portion which is folded to form a hollow bead having its opposite ends removed from the op-

posite ends of the metal strip, to leave end portions which project beyond the ends of the hollow bead, means for securing the 50 projecting end portions together with the ends of the hollow bead in proximity to and opposing each other and with one of the projecting end portions extended under one end of the beaded portion of the strip on 55 the outer side of the strip and with the other projecting end portion extended under the opposite end of the beaded portion of the strip on the inner side of the latter, and a wire in said hollow bead extended from 60 one end of the hollow bead into the opposing end of said bead, and corrugations in said bead and wire forming outwardly extended projections.

2. A metal hoop comprising a sheet metal 65 band or strip having at its opposite ends portions which are narrower than the intermediate portion of said strip to form on one side of the strip a projecting portion which is folded to form a hollow bead 70 having its opposite ends removed from the opposite ends of the metal strip, to leave end portions which project beyond the ends of the hollow bead, means for securing the projecting end portions together with the 75 ends of the hollow bead in proximity to and opposing each other and with one of the projecting end portions extended under one end of the beaded portion of the strip on the outer side of the strip and with the 80 other projecting end portion extended under the opposite end of the beaded portion of the strip on the inner side of the latter, and a wire in said hollow bead extended from one end of the hollow bead into the 85 opposing end of said bead.

In testimony whereof, I have signed my name to this specification in the presence of two subscribing witnesses.

EDWARD I. BRADDOCK.
